UNITED STATES PATENT OFFICE

RALPH MARSH, OF CRYSTAL LAKE, ILLINOIS

CORN HEADER

Application filed September 22, 1927. Serial No. 221,169.

This invention relates to a header attachment which in the form here shown, may be removably mounted on a wagon box or any other suitable supporting apparatus and by means of which the heads of grain, such as 5 Kaffir corn, for example, may be readily cut off and deposited in the wagon box or other container. One object of the invention is, therefore, to provide a complete self-contained and removable unit which may be put in any suitable location and used as a header and which thereafter may be removed and placed away for storage. Another object of the invention is to provide such a header 10 construction whereby the grain itself is held together during the cutting operation, properly fed to the cutting means and whereby the heads, trash or waste and straw are properly and automatically separated, each from 15 the other. Other objects of the invention 20 will appear from time to time in the specification and claims.

The invention is illustrated more or less diagrammatically in the accompanying 25 drawings wherein—

Figure 1 is a side elevation of the device.

Figure 2 is a horizontal cross section on line 2—2 of Figure 1 showing parts in section and parts broken away.

Figure 3 is a rear elevation of the device 30 mounted on a wagon body, showing the wagon body in section and parts of the device broken away.

Figure 4 is a vertical cross sectional detail 35 taken on line 4—4 of Figure 1.

Like parts are designated by like characters throughout the drawings and specification.

A is a wagon box or body.

B, B are short clips or channel members 40 adapted to fit over the wagon body, as shown, and to serve as a bearing support for rollers B¹ B¹ which contact the upper edge of the wagon body or side, and by means of which the device may be moved or rolled along the body into the proper position.

C is a gasoline or other engine, the details 45 of which form no part of the present invention. It is normally inclosed in the casing C¹. It is provided with a pulley C² and a

clutch which is not shown in detail, but is controlled by a handle or lever C³. C⁴ is an idler pulley mounted on an arm C⁵, which is pivoted as at C⁶ upon an extension from the frame. The frame is designated generally by the letter C⁷. The details of the frame are not described because they form no part of the invention and any suitable frame might be used. C⁸ is a tension spring 55 adapted normally to hold the idler pulley C⁴ against the belt C⁹ which passes at its lower end about the pulley C² and at its upper end about a pulley D which is fixed on a shaft D¹ carried in bearings D² D² which are themselves supported in a portion of the frame 60 C⁷. Fixed also on the shaft D¹ is a saw or other cutting member D³. While I have shown a saw, it will be understood that other means might be provided for cutting instead 65 of the saw.

E is a feed table supported on the frame C⁷, provided at its upper end with a slot E¹ within which the saw D³ extends. E² is a feeding member provided with one extension E³ and a second extension E⁴. These extensions are generally at right angles to each other, although this position is not absolutely essential and their angular relation might be different. A spring E⁵ is mounted 70 about the portion E² and is provided with an end E⁶ which bears upon the under surface of the feed table E and with another end E⁷ which bears against the upward extension E⁴. This spring tends to hold the parts in the position shown particularly in 75 Figure 1 and shown also in detail in Figure 4.

Joined to the feed table E or contacting it is a discharge apron F. Material falling 80 upon or being deposited upon this discharge apron slides across it and is discharged into the wagon body or box A and thus heads of grain cut off by the cutting apparatus fall 85 into the wagon body or other receptacle adjacent which the header as a whole is 90 mounted.

G is a trash or waste chute mounted under 95 the slot E¹ of the feed table E and beneath the cutting means D³. The small broken parts of grain and straw which would other- 100

wise slide into the wagon body fall into the trash chute and are discharged from it to the ground or to an appropriate trash receptacle not here shown.

5. **H** is a hood mounted over the cutting means as a protection to the operator.

Although I have shown in my drawings and described in this specification an operative form of my invention, many changes in 10 form, shape and arrangement of parts may be made without departing from the spirit of the invention.

The use and operation of the invention are as follows:

15. In normal operation the apparatus of this invention will be mounted upon a wagon which will be drawn through the fields where the grain has previously been cut. Operators will go with the wagon and will take bundles 20 of the grain, which may or may not have previously been formed into bundles, put them upon the feed table between the arms E^3 and E^4 which form, in effect, a feed cradle. They will then press the bundle toward the 25 cutting means, thus tilting the feed cradle E^3 , E^3 , E^4 which serves to guide the bundle to be cut, to hold it together, to prevent scattering and to effect more efficient and less wasteful cutting. The bundle is thus moved 30 into the path of the cutting means, the heads are cut off, fall upon the discharge apron, slide across its surface and into the box. The smaller parts which are broken and destroyed during the cutting operation fall into the 35 trash or waste chute and from it slide to the ground. The straw which the operator may still retain in his hands may then be thrown upon the ground or into another suitable receptacle, such, for example, as another wagon.

40. **I** claim:

1. In a grain heading assembly, a cutter, a feeder for such cutter, said feeder being adapted to receive the grain to be headed and to be moved with the grain toward the cutter, 45 a chute adapted to receive cut grain and to guide it to a suitable point of discharge, and a second chute adjacent the cutter, adapted to receive the waste from the cutting zone, to separate it from the cut grain and to discharge it from the assembly.

2. In a grain heading assembly, a cutter, a feeding part adapted to be moved forward and back toward and away from said cutter, a feed surface upon which material may be deposited to be moved to the feeding part, a chute adapted to receive the heads of grain after they have been cut.

3. In a grain heading assembly, a cutter, a feeding part adapted to be moved forward and back toward and away from said cutter, a feed surface upon which material may be deposited to be moved to the feeding part, a chute adapted to receive the heads of grain after they have been cut, and a second chute 55 adapted to receive waste matter from the cut-

ting zone and discharge it separately from the heads of grain.

4. In a grain heading assembly, a cutter, a feeding part adapted to be moved forward and back toward and away from said cutter, a feed surface upon which material may be deposited to be moved to the feeding part, a chute adapted to receive the heads of grain after they have been cut, the entire assembly being provided with supporting means whereby it may be movably and removably positioned upon any suitable support.

5. In a grain heading assembly, a cutter, a pivoted feeding frame adapted to be moved toward and away from said cutter, a feed table upon which material may be deposited to be moved to the feeding frame, a chute adapted to receive the heads of grain after they have been cut, and a second chute adapted to receive waste matter from the cutting zone and discharge it separately from the heads of grain.

6. In a grain heading assembly, a cutter, means for operating said cutter, a pivoted feeding frame adapted to be moved toward and away from said cutter and provided with means adapted normally to hold it away from such cutter, a feed table upon which material may be deposited to be moved to the feeding frame, a chute adapted to receive the heads of grain after they have been cut and to direct them to a suitable receptacle, and a second chute adapted to receive waste matter from the cutting zone and discharge it separately from the heads of grain, the entire assembly being provided with supporting means whereby it may be movably and removably positioned upon any suitable support.

7. In a grain heading assembly, a cutter, a feed table and a grain carrier pivotally mounted and formed with a plurality of extended arms, said arms extending outwardly from the pivotal axis in different directions, a spring associated with said feeder and adapted, when free to move, to hold the feeder away from the cutter.

8. In a grain heading assembly, a cutter, a feed table and a grain carrier pivotally mounted and formed with a plurality of extended arms, said arms extending outwardly from the pivotal axis in different directions, a spring associated with said feeder and adapted, when free to move, to hold the feeder away from the cutter, one of said arms normally extending upwardly and adapted to serve as a stop against which grain is pushed, the entire feeder adapted to be tilted about its pivot point and to swing with the grain toward the cutting zone.

Signed at Crystal Lake county of McHenry and State of Illinois, this 9 day of September, 1927.

RALPH MARSH.
